UNITED STATES PATENT OFFICE

2,669,190

OIL WELL PUMP

Edward J. Mullins, Los Angeles, Calif., assignor to
Alfred H. Bakke, Evanston, Ill.

Application September 22, 1950, Serial No. 186,148

5 Claims. (Cl. 103—179)

1

This invention relates to an oil well pump, and particularly to a pump capable of ejecting low gravity or heavy oil from a well, and also a pump which is efficient in its operation and can, therefore, effectively and economically pump wells which have a small oil output.

An object of my invention is to provide a novel oil well pump which is simple in construction, inexpensive to manufacture, and which requires little machine work on the barrel or on the pistons.

Still another object of my invention is to provide a novel oil well pump assembly in which the oil is withdrawn from the upper portion of the perforated liner, thereby reducing the possibility of the pump sanding up or becoming gas bound.

A feature of my invention resides in the novel arrangement and positioning of a packer below the pump, and this packer resting on top of the perforated liner and sealing off the top of this liner so that oil or other liquids cannot drop back into the top of the liner.

A further feature of my invention is to provide a novel oil well pump construction in which the pistons are formed with flexible packing thereon to engage the wall of the barrel, and a novel upper valve assembly in the pump through which the sucker rods extend.

Other objects, advantages and features of invention may appear from the accompanying drawing, the subjoined detailed description and the appended claims.

In the drawing:

Figure 1 is a fragmentary longitudinal sectional view of the lower portion of my oil well pump assembly.

Figure 2 is a fragmentary longitudinal sectional view of the upper portion of my oil well pump assembly.

Figure 3 is a sectional view taken on line 3—3 of Figure 1.

Figure 4 is a sectional view taken on line 4—4 of Figure 3.

Figure 5 is a fragmentary longitudinal sectional view of the sucker rod coupling.

Figure 6 is a sectional view taken on line 6—6 of Figure 1.

Figure 7 is a sectional view taken on line 7—7 of Figure 6.

Figure 8 is a sectional view taken on line 8—8 of Figure 2.

Figure 9 is a sectional view taken on line 9—9 of Figure 8.

Figure 10 is a side elevation of the oil draining device with parts broken away to show interior construction.

2

Referring more particularly to the drawing, the numeral 1 indicates the usual casing in the well, which extends from top to bottom of the well. The usual perforated liner is indicated at 2, and this liner is positioned within the oil sand and is cemented to the casing 1, as shown at 3, all of which is usual and well known in the art.

My pump consists of an elongated barrel 4 on the upper end of which I provide a reducing sub. 10 This sub 5 is threaded on to the barrel and the purpose of this sub is to provide an attachment for the tubing 6, which screws on to or into the sub and the tubing is of smaller diameter than the barrel 4. The tubing 6 extends to the surface and oil is withdrawn from the well through this tubing, all of which is usual and well known.

A reducing fitting 7 screws on to the lower end of the barrel 4, and a nipple 8 screws on to the fitting 7 and into the sleeve 9 of the packer 10. 20 An intake pipe 11 screws into the bottom of the sleeve 9 and extends downwardly into the liner 2. The upper end of the intake pipe 11 is perforated, as shown at 12, and oil is drawn through these perforations from the upper part of the liner 2, substantially as shown in Figure 1. The lower part 13 of the pipe 11 may consist of a settling basin for the purpose of accumulating sand.

The packer 10 surrounds the pipe 11, as previously described, and normally is somewhat smaller in outside diameter than the inside of the casing 1. The packer 10 rests on top of the liner 2, as shown in Figure 1, and weight of the pump assembly and tubing will compress the packer 10, causing the peripheral packing 14 to expand and seal the space above the top or open end of the liner 2, thus preventing any liquid from flowing back into the top of the liner. Any liquid which might seep into the casing 1 from upper levels is thus prevented from flowing back into the top of the liner 2. A standing valve 15 is seated in the fitting 7 and performs the usual function of a standing valve in a pump.

The upper valve assembly and packing 16 consists of a shell 17 which screws into the sub 5, or is otherwise fixedly mounted in this sub. A plurality of oil ports 18 are arranged adjacent the periphery of the shell 17 and each port is controlled by a ball valve 19, which seats in the port. A packing gland 20 surrounds the sucker rod 21 and prevents leakage of oil around the sucker rod and back into the pump. The check valves 19 also hold any oil above the valve assembly 16, thus maintaining the column of oil in the tubing 6.

55 A plurality of pistons 22 are mounted on the sucker rod 21 and within the barrel 4 of the

pump. The pistons 22 are spaced vertically, substantially as shown in Figure 1. The pistons are all identical in construction and each is provided with a rubber sleeve 23 which engages the wall of the barrel 4. The rubber sleeved pistons 22 will thus effectively operate in a barrel even though the inner surface of this barrel is not accurately machined or finished.

A plurality of oil ducts 24 extend vertically through each of the pistons 22 and each duct is controlled by a ball valve 25. The sucker rods 21 are secured to each of the pistons 22 and a nut 26 screws on to the lower end of the sucker rod, and this nut is provided with a slot 27 which can engage the bumper bar 28 for the purpose of unscrewing the sucker rods from the piston when desired. A sucker rod coupling 29, of usual and well known construction, is provided above the valve assembly 16 so that the entire pump can be assembled first and then attached to the sucker rods at the time it is lowered into the oil well.

Just above the pump, I may provide a fluid drain for the tubing 6 and included as a part of the tubing, which consists of a sleeve 30, extending over the riser 31. The riser is threaded into the tubing 6, as shown. An elongated slot 32 in the riser is normally covered by the sleeve 30, and consequently oil cannot leak out of this slot, however, if the tubing 6 is pulled upwardly at the surface, the slot 32 will be uncovered and oil can then drain back into the casing 1 so that there is no fluid in the tubing when this tubing is removed from the well. The sleeve 30 is threaded on to the upper portion of the tubing 6, as shown in Figure 2.

Reciprocation of the sucker rods 21 from the surface of the well will move the pistons 22 in the barrel 4. On the up-stroke of the pistons the ball valves 25 are seated and oil is drawn from the formation past the standing valve 15. Also, any oil above the pistons 22 on the up-stroke will be forced past the check valves 19 and thence upwardly into the tubing 6, and thence to the surface. On the down-stroke of the pistons 22, the standing valve 15 is closed, the valves 25 are open and oil passes through the ducts 24 to the space above the pistons 22, and within the barrel 4.

Having described my invention, I claim:

1. An oil well pump positioned in a casing, said pump comprising a barrel, a pipe extending downwardly from the barrel, said pipe having perforations therein to admit oil, an expandable packer mounted on the pipe below the barrel, said packer engaging the casing when expanded, a standing valve in the lower end of the barrel, a piston reciprocally mounted in the barrel, an upper valve assembly mounted in the upper end of the barrel, said upper valve assembly having fluid ports extending vertically therethrough, and a ball check valve seated in each of said fluid ports, a sucker rod attached to the piston, said sucker rod passing through the upper valve assembly, and a packing gland in said upper valve assembly surrounding the sucker rod, tubing attached to the upper end of said barrel and rising therefrom, said tubing having an elongated slot cut therein above said barrel, and a sleeve surrounding said tubing, said sleeve being movable longitudinally to uncover said slot, said sleeve being attached to the tubing.

2. An oil well pump positioned in a casing and a perforated liner at the lower end of the casing, said pump comprising a barrel, a pipe ex-

tending downwardly from the barrel into the perforated liner, said pipe having perforations therein to admit oil, an expandable packer mounted on the pipe below the barrel and positioned immediately above the liner, said packer engaging the casing when expanded, a standing valve in the lower end of the barrel, a piston reciprocally mounted in the barrel, an upper valve assembly mounted in the upper end of the barrel, said upper valve assembly having fluid ports extending vertically therethrough, and a ball check valve seated in each of said fluid ports, a sucker rod attached to the piston, said sucker rod passing through the upper valve assembly, and a packing gland in said upper valve assembly, surrounding the sucker rod, said piston including a rubber packing engaging the barrel and said piston having oil ducts extending longitudinally therethrough, and a ball check valve seated in each of said ducts.

3. An oil well pump positioned in a casing and a perforated liner at the lower end of the casing, said pump comprising a barrel, a pipe extending downwardly from the barrel into the perforated liner, said pipe having perforations therein to admit oil, an expandable packer mounted on the pipe below the barrel and positioned immediately above the liner, said packer engaging the casing when expanded, a standing valve in the lower end of the barrel, a piston reciprocally mounted in the barrel, an upper valve assembly mounted in the upper end of the barrel, said upper valve assembly having fluid ports extending vertically therethrough, and a ball check valve seated in each of said fluid ports, a sucker rod attached to the piston, said sucker rod passing through the upper valve assembly, and a packing gland in said upper valve assembly, surrounding the sucker rod, said piston including a rubber packing engaging the barrel and said piston having oil ducts extending longitudinally therethrough, and a ball check valve seated in each of said ducts, tubing attached to the upper end of said barrel and rising therefrom, said tubing having an elongated slot cut therein above said barrel, and a sleeve surrounding said tubing, said sleeve being movable longitudinally to uncover said slot, said sleeve being attached to the tubing.

4. An oil well pump positioned in a casing and above a perforated oil liner, said pump comprising a stationary barrel, an upper valve assembly threaded into the barrel at the upper end thereof, said upper valve assembly having fluid ports extending vertically therethrough and a ball check valve seated in each of said fluid ports, a piston reciprocally mounted in the barrel, a rubber sleeve on the piston, a sucker rod, the piston being attached to the sucker rod, said sucker rod extending through the upper valve assembly, a packing gland on the upper valve assembly surrounding the sucker rod, said piston having a plurality of ducts extending vertically therethrough, a ball check valve seated in each of the ducts, a standing valve seated in the lower end of the barrel, a pipe depending from the lower end of the pump, an expandable packer surrounding the pipe and mounted thereon, said packer resting on the perforated liner, and engaging the casing when expanded, said pipe being perforated below the packer and within the liner.

5. An oil well pump positioned in a casing and above a perforated oil liner, said pump comprising a stationary barrel, an upper valve as-

sembly threaded into the barrel at the upper end thereof, said upper valve assembly having fluid ports extending vertically therethrough and a ball check valve seated in each of said fluid ports, a piston reciprocally mounted in the barrel, a rubber sleeve on the piston, a sucker rod, the piston being attached to the sucker rod, said sucker rod extending through the upper valve assembly, a packing gland on the upper valve assembly surrounding the sucker rod, said piston having a plurality of ducts extending vertically therethrough, a ball check valve seated in each of the ducts, a standing valve seated in the lower end of the barrel, a pipe depending from the lower end of the pump, an expandable packer surrounding the pipe and mounted thereon, said packer resting on the perforated liner, and engaging the casing when expanded, said pipe being perforated below the packer and within the

10
15

liner, tubing attached to the upper end of said barrel and rising therefrom, said tubing having an elongated slot cut therein above said barrel, and a sleeve surrounding said tubing, said sleeve being movable longitudinally to uncover said slot, said sleeve being attached to the tubing.

EDWARD J. MULLINS.
